Primary Examiner — Mark Goodwin(74) *Attorney, Agent, or Firm* — Maginot, Moore & Beck(57) **CLAIM**

The ornamental design for a cab for an agricultural machine, as shown and described.

DESCRIPTION

FIG. 1 is a perspective view of a cab for an agricultural machine showing my new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The broken line showing of portions of the cab is included for illustrative purposes only and forms no part of the claimed design.
